UNITED STATES PATENT OFFICE.

LEROY R. MILLER AND CHARLEY ELMER MILLER, OF POPLAR BLUFF, MISSOURI.

STOVEPIPE-FASTENER.

1,280,520.

Specification of Letters Patent.

Patented Oct. 1, 1918.

Application filed May 23, 1916. Serial No. 99,437.

To all whom it may concern:

Be it known that we, LEROY R. MILLER and CHARLEY E. MILLER, citizens of the United States, residing at Poplar Bluff, in the 5 county of Butler and State of Missouri, have invented new and useful Improvements in Stovepipe-Fasteners, of which the following is a specification.

The present invention relates to stove 10 pipes, and more particularly to a fastener therefor, so designed to enable the clamping of the stove pipe within the opening of a chimney flue, and further enabling the pipe to be quickly and easily detached therefrom.

15 To this end, the invention consists of a thimble formed with an annular groove, a locking band seated within said groove, and means for retracting the said locking band within an annular groove formed in the 20 insertible section of the stove pipe, and thereby tightly clamping the band therearound, and firmly securing the latter in applied position.

With the above and other objects in view, 25 the invention consists in the novel features, details of construction and combination of parts which will hereinafter be more fully set forth, illustrated in the accompanying drawing and pointed out in the appended claims.

30 Figure 1 is a vertical sectional view of a chimney flue, showing the insertible section of a stove pipe connected therewith;

Fig. 2 is a perspective view of the clamping band; and

35 Fig. 3 is a detail view illustrating the application of the clamping band in clamping engagement with the insertible section of the stove pipe and in clamping engagement with the stove pipe thimble, the release position of the lever of the fastener being also indicated by dotted lines.

Referring more particularly to the accompanying drawing, in which like characters of reference refer to corresponding parts 45 in the several views, 5 denotes a chimney flue provided with the usual circular opening 6 having inserted therein the stove pipe thimble 7. The said thimble 7 is constructed of sheet metal and has its outer end 8 bent 50 to provide a laterally extending annular flange 9. The marginal edge of said flange is curved outwardly and upon itself to provide the flange with an annular groove 10. When the thimble is inserted within the 55 opening of the flue, the flange will abut the wall of the flue, and thereby limit the inser-

tion of the thimble within the flue. I have shown interposed between the flange 8 and the wall of the flue, a collar or band 11 preferably formed of asbestos and serving to an 60 extent as a gasket. The character 12 designates the insertible section of a stove pipe provided with a pair of annular beads 13 defining therebetween a groove 14, the purpose of which will be hereinafter more fully 65 set forth. Secured to the inner circumference of the thimble 7 in spaced circumferential series, are clamping arms 15 having inner hooked ends 16. As the insertible section 12 of the stove pipe is placed within the 70 thimble, it will cause these arms to expand and contact with the inner circumference of the thimble and force the hooked ends thereof in clamping contact with the inner wall of the chimney flue, thereby positively retaining the thimble in clamping engagement 75 with the opening of the chimney flue and preventing any accidental displacement of such thimble therefrom.

In order that the insertible section 12 of 80 the stove pipe may be easily and quickly detached from the thimble and also expeditiously clamped therewith, I employ a split stove pipe collar 17 having its ends connected together by the links 18 and 85 19, one of said links being pivoted to the other link intermediate its ends and the other link serving as an operating lever for expanding and contracting said collar. Said collar is provided with a flange 24 having a bead 25 at its edge. The said bead is placed within the groove 10 of the thimble and the extreme edge of the metal forming this groove is bent over to prevent the removal of the bead from the groove though 95 permitting movement of said bead in the groove.

In using the device the thimble is placed within the flue with the collar in expanded position. The stove pipe is then inserted 100 within the thimble and as the pipe passes through said thimble it will force the hooks 16 outwardly into engagement with the part of the chimney around the flue. The pipe is passed into the flue far enough to bring 105 the groove 14 thereon in alinement with the inner edge of the collar. Then by contracting said collar by means of the connecting links said collar will clamp the stove pipe in position.

110 From the foregoing description, taken in connection with the accompanying drawing,

the advantages of construction and of the method of operation will be readily apparent to those skilled in the art to which the invention relates, and while I have 5 described the principles of operation of the invention, together with the device which I now consider to be the best embodiment thereof, I desire to have it understood that the device shown is merely illustrative, and 10 that such advantages may be made when desired as are within the scope of the claims appended hereto.

I claim:

1. A device of the class described comprising a thimble having a flange thereon provided with a groove, locking arms carried by said thimble, a split collar having a flange thereon provided with a bead for engaging with said groove, and means for con-

tracting and expanding said collar to clamp 20 a stove pipe.

2. A device of the class described comprising a thimble having a flange provided with a groove, locking arms provided with hooks carried by said thimble, a split collar having a flange provided with a bead for engaging said groove, a pair of links connecting the ends of said collar together, one of said links being extended to provide an operating lever for expanding and contracting said collar on a stove pipe, and the metal forming the groove on the flange of the thimble being bent over to secure the bead within the groove.

In testimony whereof we affix our signatures.

LEROY R. MILLER.
CHARLEY ELMER MILLER.
